UNITED STATES PATENT OFFICE.

ALBERT A. SANBORN, OF NEWARK, NEW JERSEY, ASSIGNOR, BY DIRECT AND MESNE ASSIGNMENTS, TO THE CELLULOID MANUFACTURING COMPANY, OF NEW YORK, N. Y.

COLLAR OR CUFF OF CELLULOID OR OTHER PYROXYLINE MATERIAL.

SPECIFICATION forming part of Letters Patent No. 258,480, dated May 23, 1882.

Application filed September 19, 1881. (Model.)

To all whom it may concern:

Be it known that I, ALBERT A. SANBORN, of Newark, in the county of Essex and State of New Jersey, have invented a new and useful Improvement in the Manufacture of Collars and Cuffs of Celluloid or Like Plastic Material with Detachable Tabs, of which the following is a specification.

My invention relates to the manufacture of collars and cuffs of celluloid or other pyroxyline material, either with or without a lining or interlining of other material, with separately made up tabs for the button-holes.

In the ordinary way, where the tabs are cut out with the body of the collar or cuff, and therefore integral with it, I cannot make the shape between the tab and front of the collar at such angles as are often desirable; and, besides, there is great liability of cracking at the junction of the tab and collar. These difficulties I overcome by my collars or cuffs and tabs being made up separately and then put together.

Figure 1 is a plan; Fig. 2, a detailed view. In my construction, A is the collar, and B the tab, each made up separately and then cemented or otherwise united together. In this

way it will be found that besides making a perfect collar, as above stated, one that will stand the wear without cracking at the junction of the tab and collar, I effect a great saving in the cost of manufacture, as I can use the small clippings for the tabs which otherwise would be lost, and at the price of stock it is a large loss.

I am aware of the patent of S. Haufman, 83,973, but I disclaim the subject-matter of his patent, as my invention relates wholly to the manufacture of collars and cuffs of celluloid, &c., which is an entirely separate department of the manufacturing arts.

I claim—

1. The process of manufacturing collars and cuffs of celluloid or other pyroxyline material, consisting in making up the body and tab separately, and then uniting them with cement, &c., substantially as and for the purpose specified.
2. The collars and cuffs of celluloid or other pyroxyline material, constructed substantially as specified, and for the purpose set forth.

ALBERT A. SANBORN.

Witnesses:

HORACE HARRIS,
S. R. STEADMAN.
